INVENTOR

Ray C. Jordan
BY
Joseph E. Dunn
ATTORNEY

UNITED STATES PATENT OFFICE.

ROY E. JORDAN, OF NEWARK, NEW JERSEY, ASSIGNOR TO THE MOSAIC TILE COMPANY, A CORPORATION.

RECEPTACLE FOR SHEET TOILET PAPER.

Application filed March 5, 1924. Serial No. 696,964.

This invention relates to improvements in receptacles for sheet toilet paper. One of the objects of this invention is to produce a receptacle preferably composed of a single piece of ceramic material, and having means preferably comprising a bowing rib, for causing flat sheets upon insertion to be bowed outwardly at the middle portion of the sheet to enable a ready gripping of the same by the fingers for withdrawal thereof.

Another object of this invention is to produce a receptacle preferably formed of tile material and having an inner wall which will provide edge-receiving pockets to enable sheets of varying lengths within predetermined limits to be accessibly mounted within the receptacle.

Another object of the invention is to produce a receptacle, preferably composed of a single piece of tiling material, and having on the rear or back surface a centrally-located vertical depression adapted to substantially embrace the opposite corners of a post within the wall and thus to make unnecessary the excessive cutting away of said post.

Another object of my invention is to provide a receptacle, preferably formed of a single piece of tile material, with a vertically-disposed bowing-rib in the rear wall in substantial registration with a vertically-disposed withdrawal channel formed in the front wall and preferably having horizontally-disposed finger notches communicating with opposite edges thereof.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a front elevation of a receptacle embedded in a tile-faced wall;

Fig. 2 is a section on the line 2—2 of Fig. 1 illustrating the paper-bowing rib and the method of anchoring the receptacle on a post without excessive cutting of the same; and

Fig. 3 is a section of the receptacle on the line 3—3 of Fig. 1.

Referring now to these drawings, which illustrate a preferred embodiment of my invention, my receptacle or container for sheet toilet paper comprises a housing 1 composed of a single piece of ceramic, vitreous or tile material and having a face plate 2, side, top and bottom walls 3, 4, 5 and 6 respectively, and a rear wall 7. The rear wall 7, in the embodiment shown, is continuously and sinuously curved to provide on the outer surface two outwardly extending ribs 8—8^a separated by a central depression 8^b, the said ribs and depression serving to embrace and permit anchoring of the receptacle on a post 9 in the wall without excessive cutting of the post, it being merely necessary to chamfer the corners 9^a—9^b of the post for this purpose. The depression 8^b may, if desired, be filled with plaster or other suitable material. The housing is provided with a filling channel and has located within the interior of the same a bowing rib for causing the paper to be bent about the middle portion thereof, and in the preferred embodiment shown, the sinuous conformation of the rear wall hereinabove described provides on the inner rear surface of the receptacle a bowing rib 10 and end-receiving pockets 11 and 12 at opposite sides of the rib 10. The sides of these end-receiving pockets are gradually curved, as shown at 11^a—12^a to merge with the opposite side walls of the housing and to permit the contact therewith of flat pads or packages of toilet paper of varying lengths, it being understood that the opposite edges of the shorter sheets will extend further inwardly and that the middle portions will be bowed by the bowing rib 10 somewhat more than edges of longer sheets.

As shown, the outer face 2 of the receptacle is provided with a filling and withdrawal channel 13 which preferably has a length somewhat greater than the width of packages of toilet paper, so that a series of sheets or a pad or package of such sheets may be inserted through such channel 13, the opposite ends being forced downwardly into the end-receiving depressions 11 and 12, while the middle portion will be engaged

and forced outwardly by the bowing rib 10 to cause the package or series of sheets to assume a longitudinally bowed condition transversely of the said rib and of the 5 channel 13.

In the said preferred embodiment illustrated, the opposite edges of the filling channel 13 are provided with laterally-extending finger notches 14 which, with the filling 10 channel, provide space for the purpose of enabling the insertion of the fingers of the user through the front wall to engage or pinch the outermost sheet of paper to cause a further transverse bending thereof and to 15 enable withdrawal of the same through the said channel 13 as indicated in dotted lines in Fig. 2.

Having described my invention, I claim:—

1. A receptacle for packages of sheet toilet 20 paper composed of a single piece of ceramic material and comprising a package-enclosing housing having a rear wall provided on the interior of the housing with an integral

bowing rib and end-receiving pockets at opposite sides thereof, said rib providing on 25 the exterior a central depression and ribs adapted to embrace a post in the wall, and said housing having a front wall comprising a rectangular wall-tile having an opening in alignment with said bowing rib. 30

2. A receptacle for sheet toilet paper composed of a single piece of ceramic material and comprising a package-enclosing housing having an interior bowing rib, said rib providing end-receiving pockets at opposite 35 sides thereof, said housing being provided with a front wall forming a substantially-rectangular wall tile and having a vertically-extending filling and withdrawal channel registering with said bowing rib and horizontally extending finger notches in the opposite edges of the filling channel. 40

In witness whereof, I have signed my name to the foregoing specification.

ROY E. JORDAN.
